CUTTING TOOL

Edmund Greene, Narberth, and Henry F. Pearson,
Langhorne, Pa., assignors to Röhm & Haas
Company, Philadelphia, Pa., a corporation of
Delaware

Application March 16, 1944, Serial No. 526,784

2 Claims. (Cl. 77—69)

1

The present invention relates to cutting tools particularly adapted for cutting apertures in curved surfaces without requiring that the curved surface be first flattened into a sheet prior to being cut. Every point on the circumference of the aperture which may be cut in a curved surface by tools of the type herein described is equidistant from a point located centrally thereof upon the surface of curvature, when measured along a line drawn on the curved surface from the last-mentioned point to the circumference. Tools heretofore employed for cutting such openings are adapted for such purpose only when the sheet to be cut has a constant radius of curvature in all directions. They are not adapted to cut holes in sheets whose radius of curvature in one straight line direction is different from its radius of curvature when taken in another straight line direction.

For a better understanding of our invention, reference is made to the accompanying drawings wherein the various reference characters designate corresponding parts in the several figures.

Fig. 1 is an elevational view in section of one embodiment of our invention showing the cutting tool in place on a curved surface to be cut;

Fig. 2 is a plan view of the embodiment as shown in Fig. 1; and

Fig. 3 is an elevational view showing the tool in operative position.

In the embodiment of our invention shown in the several figures, stud 1 is mounted in a collar 2, fitted with bearing 3. The threaded part of stud 1 is passed through a hole in the material to be cut, represented by curved sheet X. The collar 2 is pressed against sheet X and is held in position by nut 4. The face of the collar 2 is preferably serrated to prevent slippage of the tool in relation to the sheet X. A partially slotted tubular member 5 is rotatably mounted on bearing 3 and supports parallel arms 6 which are joined together and pivoted at one end to member 5 by means of pin 7. Arms 6 may be forced downward by pressure on knob 8, which is rotatably mounted on a pin pivotally attached to said arms 6 near the extremity thereof. A cutter 10 is supported by and passes through collar 11 and is held in place by set-screw 12. The shaft of cutter 10 passes between the parallel arms 6 but is not attached thereto. Collar 11 is mounted on a flexible plate 9, one end of which is attached to the lower extremity of tubular member 5. Cutter 10 extends through a hole in plate 9 and is held in position by pins 13 attached to plate 9 which engage holes drilled in collar 11.

2

Parts 6, 8, 9, 10, and 11 are free to rotate about a vertical axis through the center of stud 1 and tubular member 5.

In operation, the tool is clamped to sheet X and pressure is applied to knob 8 which causes arms 6 to press on collar 11, thus flexing plate 9 and forcing the cutter 10 against sheet X. The device is then rotated and cuts a hole in the sheet material.

10 The additional pins 13 make it possible to place the cutter at various positions along plate 9.

It is apparent to one skilled in the art that the various parts of the device may be altered without departing from the scope of this invention.

15 In essence, this device comprises a clamping assembly and a cutting assembly, the latter being free to rotate around the clamping device and comprising a cutter mounted on a flexible plate which may be bent by the application of pressure to conform to the curvature of the surface to be cut.

The device may be constructed so that it may be operated mechanically rather than manually. Such alteration is well within the skill of the art.

25 It is also apparent that clamping means other than that shown may be employed in place of the stud, collar, and nut; and other types of cutters than that shown, for example circular cutters, may be used.

30 A device such as that shown in the drawings has been eminently suitable for use in the repair of damaged parts of aircraft which, due to streamlining design, are usually curved. It can also be used for cutting holes in any curved surface such as that of a cylinder, tank, and the like, whether made of wood, metal, resin, or the like.

We claim:

1. A tool adapted to cut apertures in curved surfaces comprising a base having a clamp, a member extending from and supported by said base and adapted to rotate about an axis concentric thereto and to said base, an arm pivoted adjacent one end thereof to and extending from said member at an angle to the axis aforesaid, a flexible plate attached at one end to and extending from the end of said member adjacent said base, a cutting element supported by and extending through an aperture in said flexible plate and having a portion thereof in slidable engagement with said arm, and means interposed between said arm and said plate whereby rotation of the arm about its pivot imparts movement to the flexible plate and cutting element supported thereby.

2. A tool adapted to cut apertures in curved surfaces comprising a base having a clamp, a member extending from and supported by said base and adapted to rotate about an axis concentric to said member and said base, a flexible support attached at one end to and extending from the end of said member adjacent said base,

a cutting element supported by and extending through an aperture in said flexible support, and means for applying pressure to said cutting element whereby it may be brought into contact with said surface and rotated about said axis.

EDMUND GREENE.
HENRY F. PEARSON.
